UNITED STATES PATENT OFFICE.

ROLAND B. DAY, OF LANSDOWNE, PENNSYLVANIA.

TREATING PETROLEUM OILS.

Application filed August 5, 1921. Serial No. 489,936.

To all whom it may concern:

Be it known that I, ROLAND B. DAY, a citizen of the United States, residing at Lansdowne, in the county of Delaware and State 5 of Pennsylvania, have invented certain new and useful Improvements in Treating Petroleum Oils, of which the following is a specification.

This invention relates to processes for 10 producing hydrocarbon materials having low boiling points from hydrocarbon materials having high boiling points.

The object of the invention is to provide a process for cracking oils by which liquid petroleum oils are subjected to a continuous treatment within a closed chamber under conditions which reduce to a minimum the possibility of the formation of carbon on the interior walls of the chamber.

20 The principle upon which the process operates is that an oil in order to be cracked into the greatest possible amount of gasoline or light hydrocarbon must be brought into contact with a heated metal and that the 25 temperature of the metal and length of time that the molecule of oil is in contact with the heated metal further controls the degree to which the molecule will react. That is, if a given molecule is allowed to come into contact with hot metal the degree to which it 30 will react, and the product that it will make will depend upon the length of time of contact and the temperature of the metal. It

35 has further been proven that different molecules in an oil require different temperatures in order to react to the best advantage, for instance, to form the maximum amount of gasoline. It is therefore necessary to provide in an apparatus for carrying out this 40 process a series of tubes or other suitable arrangement in which the temperature is raised gradually, as in a set of tubes where each tube is hotter than the last, or in a single tube where specific portions are progressively hotter than previous portions in the 45 same tube.

A particular feature of the present invention relates to the details by which carbon formation is reduced to a minimum. It has 50 been found that oil material may be treated in the liquid phase within a still to the exterior of which heat is applied, and that substantially no carbon will adhere to the interior walls of the still provided the oil is subjected to very severe agitation, that is the oil is moved rapidly over the inner surface

of the still walls. Heretofore when oil was treated in bulk in metal containers by heat applied to the exterior, coke formations rapidly rendered continued operation dangerous because of the weakened still walls, and blow outs due to such formation were common. It has been suggested that scrapers be used within stills to remove carbon formations as deposited, and other operations have included the use of false bottoms within stills. The present invention dispenses with the use of scrapers, and other forms of complicated constructions by providing for severe agitation in accordance 60 with the details of operation of certain apparatus, which details are hereinafter more 65 fully set forth.

It may be briefly stated that the invention involves preferably a tubular still with 70 in which is mounted a rotatable shaft having thereon a plurality of paddles or stirrer arms which may be rotated at a speed of about 70 revolutions per minute or faster to cause oil within the tubular still to move 75 around within the still at substantially the same rate of speed. Other details relate broadly to the use of requisite temperatures for cracking, and the fact that the still preferably should be filled full of oil during the 80 heat and agitation treatment.

The process is preferably conducted in the apparatus illustrated in the accompanying drawings, in which:

Figure 1 is a side elevation of a heating 90 furnace illustrating the exterior drive shafts, and showing their connections with the tubular retorts;

Figure 2 is a view illustrating the relative direction of rotation of the agitator shafts 95 looking in the direction of the furnace on the line 2-2 of Figure 1;

Figure 3 is a section taken on the line 3-3 of Figure 1 looking in the direction of the arrow and showing the position of the 100 retort tubes in the furnace;

Figure 4 is a view of the retort tubes with the furnace removed, illustrating the relative movement of the materials within the tubes; and

Figure 5 is an enlarged fragmentary sectional view of the retort tube illustrating the mounting of the paddles on the rotatable shaft.

Like reference numerals refer to like parts 110 in the different figures of the drawing.

Referring in detail to the drawings of the

apparatus, 1 represents the masonry construction, either concrete, stone or brick, but preferably fire brick, such as will stand severe temperatures. A suitable stack 2 is 5 provided for leading off the furnace fumes, smoke, and gases of combustion. A source of heat is provided by burners 3 located at the lower part of the furnace and fed by pipes 3^a and 3^b which feed respectively oil 10 and steam. The furnace is braced by suitable buck stays 1^a holding the same to a suitable masonry or concrete base. The flame and hot gases from the burner nozzles is projected inwardly and passed upwardly in the 15 furnace over a centrally positioned partition 4, and downwardly to ultimately escape through the stack 2. During the upward movement the heat comes in direct contact with the exterior of a plurality of longitudinally positioned retort tubes, as will be 20 described.

The drawings illustrate three cracking tubes or retort tubes 5, 6 and 7, positioned one above the other and substantially horizontally. Within the tubes 5, 6 and 7 are agitator paddles 5^a, 6^a and 7^a mounted on and adapted to turn with the shafts 5^b, 6^b and 7^b, respectively. The arrangement of the paddles is such that they are rigidly 25 fixed on the shafts and extend substantially at right angles to the line of the shaft. The paddles are arranged so as to be staggered and to form an interrupted spiral, and this arrangement is preferred because the oil in 30 conjunction with its movement around the interior of the tube also is propelled lengthwise of the tube and thus obtains the beneficial treatment resultant of the progressive movement through the increasingly hotter 35 portions of the apparatus as the lowermost tube is reached, this being nearest to the source of heat. In this manner, also, heavier materials such as any carbon and tarry materials will be carried to the lowermost point 40 in the apparatus and may be drawn off. It will be noted particularly that the paddles 5^a, 6^a and 7^a are not scraper members and they do not engage the inner surface of the tube walls to constitute scraper members. 45 Preferably the paddles are formed in the shape of a T, as this form has been considered desirable.

Materials within the tube 5 are passed to the left, referring to Figure 4, and are dropped through the communicating pipe 8 into the end of the tube 6, and similarly, such materials are passed in the opposite direction in the tube 6 and are permitted to drop through the communicating pipe 9 to the lowermost tube 7, in which latter tube the materials are again moved to the left. The direction of travel of the oil is indicated by arrows. Oil discharged from the left hand end of the tube 7 may drop downwardly through the outlet pipe 10 which is

provided with a valve 11, which latter may be adjusted to provide for the continuous removal of carbon, tar, or other relatively heavy material.

At the top of the system of cracking tubes 70 is positioned a large reservoir for oil which serves as a combined preheating chamber, reservoir and expansion chamber. This chamber is indicated by the numeral 12, and is provided with an oil inlet pipe 12^a for the admission of untreated oil and which may be controlled by a suitable valve 12^b for either batch treatment or for continuous operation. A series of test drain spigots 12^c 75 are mounted on the chamber 12 at different elevations to determine the height of the oil therein. A pipe 13 at one end of the chamber 12 leads downwardly from the floor of the chamber to the cracking tube 5. At the other end of the chamber 12 is a pipe 14 leading to the opposite end of the tube 5. A pipe 15 leads from the top of the lowermost cracking tube 7 and is connected to the top of the expansion or feed chamber 12 to carry vapor from the hotter part of the apparatus to the expansion chamber and thence to the condenser. At 16 is indicated a condenser line governed by a weighted valve, and at 17 is indicated another condenser pipe which may lead to a reflux condenser, not shown.

Drive means for driving the shafts 5^b, 6^b and 7^b is provided by a main drive shaft 18 mounted in suitable bearings 18^a, and driven by a pulley wheel 19, which latter may be operated from any suitable source of power. Referring to Figures 1 and 2, it will be noted that the shaft 18 moves clockwise and turns a sprocket gear 20, which in turn operates a continuous chain 21, which latter extends over sprocket gears 5^c, 6^c and 7^c, which are mounted respectively on the shafts 5^b, 6^b and 7^b. The arrows in Figure 2 indicate the relative direction of rotation of the sprocket wheels and the conveyor shafts. At the opposite end of the cracking tubes is a second drive chain 21^a connecting the opposite end of the drive shaft 18 with the shafts 5^b, 6^b and 7^b.

The process has been satisfactorily conducted in apparatus like that described above in which the retort tubes were of six inch bore and in which the agitating members on the shaft did not constitute scrapers and the ends of which were spaced from the inner walls of the tube. In conducting the process in the above described apparatus, oil is introduced into the expansion chamber 12 through the pipe 12^a, and from this chamber it circulates downward filling up the different tubes of the system. When the agitator members on the shafts are actuated the oil moves downward through the tubes, and at the same time is subjected to the severe agitating movement caused by the high speed

rotation of the shaft and paddles. This movement should be about 70 revolutions per minute and might well be faster. Different oils will logically require different speeds 5 and it may be said that the heavier the oil a correspondingly higher speed is desirable. The process has been conducted satisfactorily on California oils having specific gravities of 11° B. to 12° B., and yields of 60 per cent 10 of cracked distillate were obtained in which specific gravities of as high as from 30° B. to 40° B. were obtained, yielding as high as 47 per cent of gasoline with an end point of 190° C. and a specific gravity of 54° B. In 15 these operations the only carbon formed was in a finely divided state in the heavy tar which was drawn off and which amounted to less than one per cent of the total oil pumped into the apparatus.

20 The blast of flame from the burners 3 provides a temperature in the lower retort higher than the temperature of the upper retort. Thus when a temperature of 1000° F. is present in the lower retort, the temperature in the upper retort will probably be about 200° F. less, or about 800° F. The process includes a temperature range varying from 550° F. to 1000° F. and above for the upper and lower retort tubes, respectively. The difference in temperature between the upper and lower tubes is accounted for in part by the distance from the source of heat, and by the fact that fresh oil is introduced into the upper retort tube. This 25 gradual heating has proved advantageous because every particle of oil is at some time within its travel subjected to the degree of temperature best suited for cracking it. Pressures within the apparatus may vary 30 from 40 to 150 pounds per square inch.

40 Progressive heating, progressive cracking, surface contact, speed of agitation and time are all variable and interdependent on each other. Time cannot be stated specifically. 45 The important point, however, is that it takes a given fraction of a B. t. u. to crack a given molecule. At a high temperature it would take less time than at a low temperature. Time therefore is used in a molecular 50 sense, and not as a measurement of the time the whole body of oil is subjected to heat. Thus time is dependent on temperature and upon surface contact and varies with these two conditions. The other points, pressure, 55 speed, progressive heating and cracking, are means of putting the principle into effect. Time, particularly, and surface contact are important. This does not refer, as stated above, to the time that the total oil is exposed to the heat, but refers to the time that 60 each molecule is in contact with the hot metal at the right temperature. The speed of the stirring member controls the speed of the moving body of oil and therefore controls the speed of a given molecule traveling

along the inner wall of the tube. This is the hottest point in the section of the tube, and if the temperature at that point is right for this molecule, it will crack and pass out as vapor, allowing another to take its place. 70 If the conditions are not right, the molecule will move down the tube or into the mass of oil again and away from the surface to later be exposed farther along at a hotter point. The apparatus described and illustrated in the accompanying drawing serves to carry out the process based on the above statement of principle.

I claim:—

1. In the production of low boiling hydrocarbons from high boiling hydrocarbon oils, the process which comprises maintaining a first treatment chamber constantly full of liquid oil, maintaining a pool of oil in a second chamber and at a level above that of said first chamber and constantly connected by a communicating body of liquid with the oil of said first chamber, said communicating body of liquid extending from the interior and top of said first chamber to the interior and bottom of said second chamber, applying heat to the exterior of said first chamber sufficient to crack some of the oil therein, and leading off aeriform products from above said pool of oil, the even heating of liquid within said first treatment chamber being effected and the formation of carbon on the inner surface of the walls of said first chamber being prevented solely by violently agitating the liquid material continuously during the application of heat to said first chamber.

2. In the production of low boiling hydrocarbons from high boiling hydrocarbon oils, the process which comprises maintaining two chambers in a furnace constituting a first treatment chamber and a second treatment chamber at a level above said first chamber and spaced from it and connected to it by an open passageway providing ported communication leading from the upper interior of said first chamber into the lower interior of said second chamber, maintaining both said first and said second chambers and said passageway constantly full of liquid oil, agitating the oil in said chambers to prevent incrustation of solid material on the walls thereof, and subjecting said chambers to externally applied heat sufficient to create cracking temperatures within both said chambers, the heat being applied more intensely to said first chamber than to said second chamber.

3. In the production of low boiling hydrocarbons from high boiling hydrocarbon oils, the process which comprises maintaining two chambers in a furnace constituting a first treatment chamber and a second treatment chamber at a level above said first chamber and spaced from it and connected

to it by an open passageway providing port-
ed communication leading from the upper
interior of said first chamber into the lower
interior of said second chamber, maintain-
ing both said first and said second chambers
and said passageway constantly full of
liquid oil, and subjecting said chambers to
externally applied heat sufficient to create
cracking temperatures within both said
chambers, the heat being applied more in-
tensely to said first chamber than to said

second chamber, the even heating of liquid
within said chambers being effected and the
formation of carbon on the inner surface of
the walls of said chambers being prevented ¹⁵
by violently agitating the liquid material
around the interior of each chamber, con-
tinuously in one direction in each respective
chamber, during the application of heat to
said chambers. ²⁰

In testimony whereof I affix my signature.
ROLAND B. DAY.
